FILTER AMPLIFIER

Takeo Matsuzaki and Hitoshi Watanabe, Tokyo, Japan, assignors to Nippon Electric Company, Limited, Tokyo, Japan, a corporation of Japan

Filed Mar. 22, 1961, Ser. No. 97,484

Claims priority, application Japan, Mar. 25, 1960, 35/19,084

3 Claims. (Cl. 330—31)

This invention relates to a filter amplifier composed of a combination of a constant impedance type network and a transistor circuit.

It is known to provide four-terminal filters of the constant impedance type (in specific bands) by the interconnection of two-terminal reactive impedances. Such filters result in a certain amount of attenuation of energy because of either the resistances or those resistances intentionally added.

It is an object of this invention to provide filters with simplified structures of the above type which are substantially lossless with respect to the signal energy. This is accomplished by connecting transistors in the network so that the gain in the transistors will compensate for resistance losses.

The above-mentioned and other features and objects of this invention and the manner of attaining them will become more apparent and the invention itself will be best understood by reference to the following description of an embodiment of the invention taken in conjunction with the accompanying drawings, in which:

FIGS. 1 (a) to (h) inclusive are circuit diagrams to explain the principles of this invention. FIG. 2 and FIG. 3 are the construction diagrams of some embodiments of this invention.

Among FIGS. 1 (a) to (h) inclusive, which are circuit diagrams for explaining the principles of a filter amplifier of this invention, FIG. 1 (a) shows a four-terminal voltage network composed of two-terminal constant impedance circuit type network in which two resistances r_1 and r_2 are connected parallel to two reactive impedances Z_1 and Z_2 , respectively, and those two parallel circuits are connected further in series as shown in the drawing. The resistances r_1 and r_2 include the inherent resistance of the impedances Z_1 and Z_2 . The input impedance Z is as follows:

$$Z = \frac{r_1 Z_1}{r_1 + Z_1} + \frac{r_2 Z_2}{r_2 + Z_2} \quad (1)$$

If

$$Z_1 Z_2 = r_1 r_2 \text{ and } r_1 = r_2 = r$$

then, the input impedance Z becomes as follows:

$$Z = \frac{r_1 Z_1}{r_1 + Z_1} + \frac{r_2 Z_2}{r_2 + Z_2} = \frac{r_1 Z_1 + r_2 Z_2}{r_1 + r_2 + Z_1 + Z_2} = \frac{r_1 Z_1 + r^2}{r + Z_1} \quad (2)$$

Therefore, if the source voltage E is applied to this network, the output voltages V_1 and V_2 across the terminals of the resistances r_1 and r_2 become, respectively, as follows:

$$V_1 = \frac{E}{r + Z} \cdot \frac{r_1 Z_1}{r_1 + Z_1} = \frac{V}{Z} \cdot \frac{r_1 Z_1}{r_1 + Z_1}$$

$$V_2 = \frac{E}{r + Z} \cdot \frac{r_2 Z_2}{r_2 + Z_2} = \frac{V}{Z} \cdot \frac{r_2 Z_2}{r_2 + Z_2} \quad (65)$$

inasmuch as $Z_1 Z_2 = r^2$. Finding the difference of the two outputs V_1 and V_2 ,

$$V_1 - V_2 = \frac{V}{Z} \left(\frac{r_1 Z_1}{r_1 + Z_1} - \frac{r_2 Z_2}{r_2 + Z_2} \right) = \frac{V}{r} \cdot \frac{r^2 (Z_1 - r^2/Z_1)}{(r + Z_1) (r + r^2/Z_1)} = V \cdot \frac{Z_1^2 - r^2}{(r + Z_1)^2} = V \cdot \frac{Z_1 - r}{Z_1 + r} \quad (3)$$

2

Since

$$|Z_1 - Z_2 + r|$$

is equal to 1, the difference $V_1 - V_2$ is of a constant amplitude. This relation is the same as the relation of the well-known two terminal constant impedance network.

If $Z_1 = Z_2$, and $r_1 = r_2 = r$, then the input impedance Z is as follows:

$$Z = \frac{r_1 Z_1}{r_1 + Z_1} + \frac{r_2 Z_2}{r_2 + Z_2} = 2 \frac{r Z_1}{r + Z_1} \quad (4)$$

Therefore, the difference $V_1 - V_2$ is as follows:

$$V_1 - V_2 = \frac{V}{Z} \left(\frac{r_1 Z_1}{r_1 + Z_1} - \frac{r_2 Z_2}{r_2 + Z_2} \right) = \frac{V}{Z} \left(\frac{r Z_1}{r + Z_1} - \frac{r Z_1}{r + Z_1} \right) = 0 \quad (5)$$

This means that the output becomes zero.

Thus, the Equations 2 and 4 indicate that the same design theory holds as that of the lattice-type network where if the series and the lattice element impedances Z_1 and Z_2 are so chosen that they nearly satisfy the relations $Z_1 Z_2 = r^2$ and therefore

$$\sqrt{\frac{Z_1 Z_2}{r^2}} = 1$$

for the transmission band, (10) $Z_1 = Z_2$, and therefore

$$\sqrt{\frac{Z_1}{Z_2}} = 1$$

for the attenuation band, then any filter can be designed. It is therefore possible to design a four terminal voltage filter with the network of FIG. 1(a). Furthermore, while two sets of impedances Z_1 and Z_2 are required in a lattice-type network only one set is sufficient for the network of this invention, without any transformation of the network.

Referring to FIG. 1(b) wherein a two-terminal constant impedance circuit type network in which two resistances r_1 and r_2 are connected in series with two impedances Z_1 and Z_2 respectively, and those two series circuits are connected further in parallel, the input impedance Z becomes as follows:

$$Z = \frac{1}{\frac{1}{r_1 + Z_1} + \frac{1}{r_2 + Z_2}} = \frac{(r_1 + Z_1)(r_2 + Z_2)}{r_1 + r_2 + Z_1 + Z_2}$$

If $Z_1 Z_2 = r_1 r_2$, and $r_1 = r_2 = r$, then the input impedance Z is as follows:

$$Z = \frac{(r + Z_1)^2}{(r + Z_1)^2} \cdot r = r \quad (6)$$

The difference of the output voltages is as follows:

$$V_1 - V_2 = \frac{V}{Z} \left(\frac{r_1 (r_2 + Z_2)}{r_1 + r_2 + Z_1 + Z_2} - \frac{r_2 (r_1 + Z_1)}{r_1 + r_2 + Z_1 + Z_2} \right) = \frac{V}{r} \cdot \left(\frac{r Z_1}{r + Z_1} - \frac{r Z_2}{r + Z_2} \right) = V \cdot \frac{Z_1 - r}{Z_1 + r} \quad (7)$$

Thus, as in the case shown by Equation 3, an output of a constant amplitude is obtained.

If $Z_1 = Z_2$, and $r_1 = r_2 = r$, then the impedance Z and the difference $V_1 - V_2$ as follows:

$$Z = \frac{(r + Z_1)^2}{2(r + Z_1)} = \frac{r + Z_1}{2} \quad (8)$$

$$V_1 - V_2 = \frac{V}{Z} \left(\frac{r(r + Z_1)}{2(r + Z_1)} - \frac{r(r + Z_1)}{2(r + Z_1)} \right) = 0 \quad (9)$$

Thus, the Equations 6 to 9 are obtained, which holds the same relations as the Equations 2 to 5 and thus also make it possible to design a voltage filter. As has been described, the design Equations 2, 3 or 6, 7 for four-terminal networks of FIGS. 1(a) and (b) which are derived from

the two-terminal constant impedance type network containing resistances, are the conditions for the transmission band in designing a filter of the lattice-type network having the elements Z_1 and Z_2 , while the Equations 4, 5 or 8, 9 are the conditions for the damping band. By choosing the elements Z_1 and Z_2 so as to satisfy both of these conditions the required band filter is obtained. The design of the elements Z_1 and Z_2 which satisfy the Equation 10 is the same as Cauer's lattice-type filter design theory, and the well-known design table is already published. Since, however, two sets of elements Z_1 and Z_2 are generally required in realizing a lattice-type circuit, the circuit is usually transformed into a ladder-type circuit which decreases the number of elements by half although it generally requires mutual inductance or an ideal transformer. Rieger's or Jaumann's transformation is an example of the latter. A detailed description of the Cauer type filter appears in the publication entitled "Synthesis Linear Communication Network," written by W. Cauer and published by the McGraw Hill Book Company, 1958, pages 111-112. The Jaumann and Rieger type filters are described on page 370 of said publication.

Since, in this invention, a filter is realized with only a set of elements Z_1 and Z_2 of Cauer's design theory itself and with only two additional resistance elements r 's, it is very economical. However, the network of FIG. 1(a) or (b) as it is, is nothing but a voltage filter whose output terminals are open. There are losses in transmission due to the resistance effects.

This invention intends to realize a lossless filter by making the resistances r included in the constant of a transistor circuit.

Now referring to the network of FIG. 1(c) wherein the impedance Z_2 and the resistance r_2 of FIG. 1(b) are interchanged, the input impedance Z is the same as that of FIG. 1(b), but the output voltage $V_1 - V_2$ is different therefrom and is as follows:

$$V_1 - V_2 = \frac{V}{Z} \left\{ \frac{r_1(r_2 + Z_2)}{r_1 + r_2 + Z_1 + Z_2} - \frac{Z_2(r_1 + Z_1)}{r_1 + r_2 + Z_1 + Z_2} \right\} \quad (10)$$

If $Z_1 = Z_2$ and $r_1 = r_2 = r$, then

$$V_1 - V_2 = V \frac{r - Z_1}{r + Z_1} \quad (11)$$

Thus, if $Z_1 = Z_2$, only the output voltage changes and is expressed in term of that impedance Z_1 as shown in the Equation 11. It will be understood from this fact that the transmission loss varies with the frequency and that the network of FIG. 1(c) is a constant resistance damping equalizer whose input impedance is given by $Z = r$.

From the networks of FIG. 1(a) and (b), four-terminal voltage filters of Rieger type shown in FIG. 1(d) and (e) and those of Jaumann type shown in FIG. 1(g) and (h) are also obtained by using a transformer T. FIG. 1(f) is a network which is similar to that of FIG. 1(b) and in which the output terminals are from the midpoints of the impedances and the resistances. Here, the resistances r_1 and r_2 are so chosen that $r_1 = r_2 = r$, and the impedances Z_1 and Z_2 are so chosen that $Z_1 Z_2 = r^2$ in the transmission band and $Z_1 = Z_2$ in the damping band. In the networks shown in FIGS. 1(d)-(h), if

$$r_1 = r_2 = r \rightarrow 0$$

or ∞ , they become equivalent to the well-known Rieger or the Jaumann circuit.

According to this invention, a filter amplifier is provided based upon the above principles, in whose gain, the losses of the voltage filter are compensated by substituting the effective resistances of the transistor base or emitter for the above-mentioned resistances $r_1 = r_2 = r$.

FIG. 2 shows construction diagrams obtained by applying this invention to the network of FIG. 1(a). In FIG. 2(a), similar N type transistors T_1 and T_2 are used in a grounded emitter type amplifier. Let the resistance of the base, of the emitter, and of the collector be r_b , r_e , and

r_c , respectively, then the input impedances of the transistors T_1 and T_2 for emitter grounding and for base grounding, respectively, are as follows:

For emitter grounding,

$$r_b + r_e \frac{r_c}{r_c(1-\alpha) + r_e} = r_b + \frac{r_e}{1-\alpha} \quad (12)$$

for base grounding,

$$r_e + r_b \frac{r_c(1-\alpha)}{r_b + r_e} = r_e + r_b(1-\alpha)$$

where

$$\alpha = \frac{I_e}{I_c}$$

or α is a current gain for base grounding (I_c a collector current, and I_e , an emitter current).

In FIG. 2(a), for example, transistors T_1 and T_2 and adjustable resistances r'_1 and r'_2 are used instead of the resistances r_1 and r_2 of the network shown in FIG. 1(a). By adjusting one or the other of the adjustable resistances r'_1 and r'_2 so that the following equations are satisfied:

$$r_1 = r'_1 + r_b + \frac{r_e}{1-\alpha} \quad (13)$$

$$r_2 = r'_2 + r_b + \frac{r_e}{1-\alpha}, \quad r_1 = r_2 = r$$

and by letting the impedances Z_1 and Z_2 satisfy the Equations 2 and 4 or 6 and 8, then it is obvious that the filter amplifier mentioned above can be designed. Here, the adjustable resistances, r'_1 , r'_2 may be inserted either on the base side or on the emitter side. It is only necessary to adjust one of them so as to satisfy the Equation 13. By utilizing the difference of the amplified output of the transistors T_1 and T_2 , the filter base on the principle of FIG. 1(a) can consequently be designed.

FIG. 2(b) and FIG. 2(c) show filter amplifiers of this invention, wherein a N type and a P type grounded emitter amplifier are used and wherein two N type grounded base amplifiers are used respectively. The resistances r'_1 and r'_2 of FIG. 2(c) are so-chosen as to satisfy the Equation 13. In FIG. 2(d), only one transistor T_1 is used, and the output of the resistance connected in parallel to the impedance Z_2 is taken out directly, only a voltage applied to the resistance comprising the input resistance of the transistor T_1 being amplified.

In FIG. 3 which shows Jaumann type embodiments of this invention, (a) shows a circuit in which two transistors T_1 and T_2 are used in emitter ground type and the difference of the outputs of the transistors T_1 and T_2 is taken out by a transformer T; (b) and (c) show circuits wherein two N type and a P type transistor are used respectively; (d) and (e) show circuits in which only one transistor T_1 is used and the output of the resistance connected in series to the impedance Z_1 is directly taken out, only a voltage applied to the resistance comprising the input resistance of the transistor T_1 being amplified. The circuit of FIG. 3(f) is a damping equalizer as given by the Equation 11, where the outputs of the transistors T_1 and T_2 are taken as shown in FIG. 1(c).

As explained above in detail, it is necessary in order to apply this invention generally, that the input admittance Y_{11} (or impedance Z_{11}) and the transmission admittance Y_{12} (or impedance Z_{12}) of the resultant admittance (or resultant impedance) of the four-terminal network; in which two sets of two-terminal admittances Y_1 and Y_2 (or impedances Z_1 and Z_2) and conductances $g_1 = g_2 = g$ (or resistances $r_1 = r_2 = r$) are connected as in FIG. 1(a) or (b), namely,

$$Y_{11} = \frac{1}{1+Y_1} + \frac{1}{1+Y_2} \quad (14)$$

$$Y_{12} = \frac{1}{1+Y_1} - \frac{1}{1+Y_2}$$

as standardized according to the relation $g_1=g_2=1$ (in case of an impedance system, $r_1=r_2=1$ and $Y \rightarrow Z$); be so chosen that $|Y_{11}|=|Y_{12}|=1$ in the transmission region and $Y_{12}=0$ in the attenuation band. Conversely, solving the Equation 14 for $Y_1 Y_2$, the following results are obtained. 5

$$Y_1 = \frac{2 - (Y_{11} + Y_{12})}{Y_{11} + Y_{12}}, \quad Y_2 = \frac{2 - (Y_{11} - Y_{12})}{Y_{11} - Y_{12}} \quad (15)$$

This means that, in the transmission band, approximately $Y_1 Y_2 = 1$; and in the attenuation band approximately $Y_1 = Y_2$. In general, if the admittances Y_{11} and Y_{12} are functions of complex variables, Y_1 and Y_2 are also realized by functions of complex variable. Even if the real parts of the admittances Y_{11} and Y_{12} are negative, if 10

$$R(Y_{11} + Y_{12}) >= 2$$

15

it is possible to make the real parts of the admittances Y_1 and Y_2 positive. Again, even if either of the admittances Y_{11} and Y_{12} is a negative real function, the admittances Y_1 and Y_2 can be made positive. From the theory of network design, it is not always necessary that the admittances Y_{11} and Y_{12} of Cauer's design theory should be pure imaginary functions; they can be complex numbers instead. 20

We claim:

1. A four terminal filter amplifier comprising: 25
  - (A) a pair of input terminals;
  - (B) first and second networks connected in series to said input terminals, at least one of the networks including a transistor,
    - (1) said first network comprising first impedance and resistance means connected in a first parallel circuit,
    - (2) said second network comprising second impedance and resistance means connected in a second parallel circuit,
    - (3) said parallel circuit being connected to each other in series across said input terminals,
    - (4) the impedances and resistances of said first and second impedance and resistance means satisfying the relation in the pass-band of said filter amplifier that the product of resistances is substantially equal to the product of impedances, and in the attenuation band of said filter amplifier that the impedances of the impedances means are substantially equal, 30
    - (5) at least one of said resistance means comprising the input resistance appearing between the base and emitter electrodes of said transistor,
  - (C) means for deriving an output voltage substantially proportional to the difference between the voltage which appears across said first and second resistance means respectively,
    - (1) at least one of said voltages including the output voltage appearing across the emitter and collector electrodes of said transistor; 55
  - (D) and a pair of output terminals connected to said deriving means.
2. A four terminal filter amplifier comprising: 60
  - (A) a pair of input terminals;
  - (B) first and second networks connected in parallel across to said input terminals, at least one of said networks including a transistor;
    - (1) said first network comprising first impedance and resistance means connected in series,
    - (2) said second two-terminal network comprising second impedance and resistance means connected in series, 65

(3) the impedances and resistances of said first and second impedance and resistance means satisfying the relation in the pass-band of said filter amplifier that the product of resistances is substantially equal to the product of impedances, and in the attenuation band of said filter amplifier that the impedances of the impedance means are substantially equal,

(4) at least one of said resistance means comprising the input resistance appearing between the base and emitter electrodes of said transistor,

(C) means for deriving an output voltage substantially proportional to the difference between the voltages which appear across the first and second resistance means, respectively,

(1) at least one of said voltages including the output voltage appearing across the emitter and collector electrodes of said transistor;

(D) and a pair of output terminals connected to said deriving means.

3. A four terminal filter amplifier comprising:

(A) a pair of input terminals;

(B) first and second networks connected in parallel to said input terminals, at least one of said networks including a transistor,

(1) said first network comprising first impedance and resistance means connected in series,

(2) said second network comprising second impedance and resistance means connected in series,

(3) the impedance and resistance of said first and second impedance means and resistance means satisfying the relation in the attenuation band of said filter amplifier that the product of resistance is substantially equal to the product of impedances, and in the pass-band of said filter amplifier that the impedances of the impedance means are substantially equal,

(4) at least one of said resistance means comprising the input resistance appearing between the base and emitter electrodes of said transistor;

(C) means for deriving an output voltage substantially proportional to the difference between the voltages which appear across one of said first and second impedance means and one of said first and second resistance means,

(1) at least one of said voltages including the output voltage appearing across the emitter and collector electrodes of said transistor.

(D) and a pair of output terminals connected to said deriving means.
